C. H. OVERLY & O. A. THOMPSON.

PULLING MACHINE.

APPLICATION FILED APR. 15, 1914.

1,110,004.

Patented Sept. 8, 1914.

UNITED STATES PATENT OFFICE.

CHARLES HERMAN OVERLY AND OWEN ALONZO THOMPSON, OF INDEPENDENCE, KANSAS, ASSIGNORS OF ONE-FOURTH TO WILLIAM WELCH CURTAIN, OF INDEPENDENCE, KANSAS, AND ONE-FOURTH TO THOMAS GEORGE LANEY, OF ERIE, KANSAS.

PULLING-MACHINE.

1,110,004.

Specification of Letters Patent.

Patented Sept. 8, 1914.

Application filed April 15, 1914. Serial No. 831,948.

To all whom it may concern:

Be it known that we, CHARLES H. OVERLY and OWEN A. THOMPSON, citizens of the United States of America, residing at Independence, in the county of Montgomery and State of Kansas, have invented certain new and useful Improvements in Pulling-Machines, of which the following is a specification.

10 The present invention relates to improvements in pulling machines to be used for the purpose of pulling rods from bored wells.

The primary object of the invention is to 15 provide improved means for raising the rods or tubes when it is necessary to connect more tubes or rods for the purpose of placing them in the well, by providing a mechanical lift to release the elevator from 20 under the knuckle of the tube or rod, after the tubes have been hoisted by the hoisting machine, and the invention is further designed to provide certain other improvements as will be apparent from the drawings.

25 The invention consists in certain novel combinations and arrangements of parts as will be hereinafter more fully described and claimed.

30 In the accompanying drawings we have illustrated one complete example of the physical embodiment of our invention constructed according to the best mode we have so far devised for the practical application 35 of the principles of the invention.

Figure 1 is a side elevation of a machine embodying the novel features of our invention. Fig. 2 is a front view of the lower portion of the pulling machine of Fig. 1. 40 Fig. 3 is a view showing detached, the actuating parts of the pulling machine.

In the preferred embodiment of our invention the pulling machine comprises a mast which includes two side arms 1-1' 45 which are suitably connected and braced, and at their bottoms are joined by the large beams 2-2'. At the upper end of the mast the usual wheel or pulley 3 is journaled, and when the mast is in working position, 50 as shown in Fig. 1, suitable guy ropes (not shown) and braces are employed to hold the mast in position.

The hoisting mechanism of the machine includes a reel 4 supported on the horizontal

shaft 5, between the two arms 1-1' and the 55 shaft 5 is journaled in bearings in two upright posts 6-6 that are secured each at the inner sides of the arms 1-1' and bolted to the cross beams 2-2. In connection with the reel 4 a pair of brake drums 7-7 are 60 employed, and additional reels 8-8 are provided between these two drums over which the power rope 9 may be wound. The central reel 4 is for the pull rope 10 which is wound upon the reel, and extends up 65 over the pulley 3, and by means of a hook 11 is adapted to engage the bail or eye 12 of the elevator 13 which is connected, as in Fig. 1, to a lifting tube 14.

Each of the brake drums 7-7 is provided 70 with a brake band as 15-15, and each of these bands is connected to a crank shaft 16 which is journaled in bearings 17, bolted to one of the beams 2. One end of each of the bands, as 18, is fastened as by bolts 19 75 to the front beam 2, and the free end of each band 15 is swiveled or journaled on the crank shaft 16, as at 20. Thus, it will be understood that the brake bands have their forward ends anchored or attached to 80 the front beam by the bolts 19, and their rear or free ends are loosely connected with the crank shaft, it being of course understood that the bands pass over the drums 7, and are adapted to frictionally contact 85 therewith. Thus, by movement of the crank shaft, the brake bands are applied to the drums, and the reels or hoisting mechanism are controlled.

The operating lever 21 which is journaled 90 in brackets 22 fixed to the front of the beam 2, has a shorter arm 23 extending back through the mast toward the crank shaft, and this short arm of the lever is linked to the crank shaft by means of the link 24. In 95 Fig. 3, all the actuating parts are shown in full lines, and it will be apparent that when the lever 21 is thrown to the left, the movement of the arm 23, link 24, and crank shaft 16, will apply the brake bands to the 100 brake drums to control the rotation of the reels.

In connection with the braking mechanism we employ vertically slidable, or movable bearings for the hoisting device. In the 105 drawings it will be seen that the shaft 5 is journaled in heads 25, which are slidable in the brackets 26, and each of these heads 25

has a link 27 pivoted thereto, which links are connected by the cross bar 28 which is journaled in the brackets 29 secured to the posts 6—6. This cross bar 28 insures that 5 the two bearing heads 25 shall move or slide in unison. The cross bar 28 is in reality a rock bar, and it is rocked from the crank shaft 16, the bar and shaft being connected by a link 28' which is slotted and loosely 10 pivoted or journaled to each bar. Thus, it will be seen from the inspection of Fig. 3, that when the operating lever 21 is moved to the left, the connecting links will be actuated so that the journal bearing head 25 will 15 be caused to move downwardly in the direction of the arrow, and thus move the reel and drums with it. The parts are returned to their normal position in Figs. 1 and 3, by the reverse movement of the lever 21, and 20 the load on the drums and reel, hold the device in the upper normal position.

In use, assuming that the elevator is placed under a knuckle of a rod, for the purpose of holding the rod and connecting 25 more rods to be placed in the well, after such additional rods are connected up, they are held by the elevator which rests upon the top of the well casing, and in order to disengage and free the elevator from the 30 knuckle, it is necessary to lift this weight a slight distance to release the elevator. This lifting is accomplished by a continuation of the lever movement which applies the brake to the drums, to the left in Fig. 3, and it 35 will be seen that the reels are under the control of the operator while this lifting movement is going on, and the lifting movement is accomplished by the bodily downward movement of the drums and reel. The 40 use of these slideable journal bearings for the drums obviates the necessity for man-

ually operating the brake drums to give this lift, which is known as the "kick off."

Having thus fully described our invention, what we claim as new and desire to 45 secure by Letters Patent, is:—

1. The combination in a pulling machine with its mast and winding mechanism, of movable journal supports for said winding mechanism, braking means for the winding 50 mechanism, and means connected with the braking means for bodily moving the winding mechanism in its journal bearings.

2. The combination in a pulling machine with its mast of a winding drum and its 55 brake and movable journals for said drum, means for actuating the brake, and connections from said actuating means adapted to bodily move the winding drum after the brake has been applied.

3. The combination in a pulling machine with its mast, of a winding device supported in movable bearings, braking mechanism, the operating lever for said braking mechanism, a rock bar actuated from the operating lever, and links connecting said bar with the movable winding mechanism.

4. The combination in a pulling machine with its mast, of a winding mechanism movably supported on said mast and including 70 brake drums, means for braking said drums, a pair of slideable bearings for the winding mechanism, a rock bar connected with said bearings, and connections between said rock bar and the brake operating mechanism.

In testimony whereof we affix our signatures in presence of two witnesses.

CHARLES HERMAN OVERLY.
OWEN ALONZO THOMPSON.
